UNITED STATES PATENT OFFICE

152,394

DESIGN FOR A STOMACH EXERCISER OR SIMILAR ARTICLE

John J. Ceverha, Chicago, Ill.

Application June 26, 1947, Serial No. 139,932

Term of patent 14 years

(Cl. D83—1)

To all whom it may concern:

Be it known that I, John J. Ceverha, a citizen of the United States, residing in Chicago, in the county of Cook, State of Illinois, have invented a new, original, and ornamental Design for a Stomach Exerciser or Similar Article, of which the following is a specification, reference being had to the accompanying drawings, forming a part thereof.

Figure 1 is a top plan view of a stomach exerciser or similar article, showing my new design.

Figure 2 is a bottom view of the same.

Figure 3 is a rear edge view of the same.

Figure 4 is a front edge view of the same.

Figure 5 is a sectional view taken along the line 5—5 of Figure 1.

Figure 6 is a sectional view taken along the line 6—6 of Figure 1.

Figure 7 is a sectional view taken along the line 7—7 of Figure 1.

I claim:

The ornamental design for a stomach exerciser or similar article, as shown.

JOHN J. CEVERHA.
